UNITED STATES PATENT OFFICE.

GEORGE T. SHEARER, OF ATLANTA, GEORGIA.

HOUSE NUMBER.

Application filed September 18, 1924. Serial No. 738,444.

To all whom it may concern:

Be it known that I, GEORGE T. SHEARER, a citizen of the United States, residing at Atlanta, in the county of Fulton and State of Georgia, have invented a certain new and useful Improvement in House Numbers, of which the following is a specification.

My invention relates broadly to an improved construction of day and night house number box, and more particularly to an arrangement of illuminating panels in a house number box by which identification symbols may be exhibited both at night and during the day in a particularly desirable manner.

One of the objects of my invention is to provide a construction of day and night house number box which may be readily manufactured inexpensively on a quantity production basis.

Still another object of my invention is to provide a combined day and night house number box which may be utilized both as an identification sign and also as an illuminating means for a house entrance.

Still another object of my invention is to provide an arrangement of panels which will enable numbers, figures, or other identification marks to be exhibited to good advantage both at night and during daylight.

A still further object of my invention is to provide a combined day and night house number box which may be readily manufactured from pressed metal with the identification symbols carried in individual pressed metal boxes secured to a front panel in the form of a frame arranged to form the front of an illuminating box body.

My invention further resides in the construction of a day and night house number box and in the means for supporting identification panels therein where the box may be entirely enclosed and rendered dust and bug proof.

Still other and further objects of my invention will be understood from the specification hereinafter following by reference to the accompanying drawings wherein:

Figure 1 is a perspective view of the combined day and night house number box suspended from the ceiling of a porch and arranged to serve both as an identification means for the home and as an illuminating means for the house entrance; Fig. 2 is a cross-sectional view through the house number box showing the arrangement of the il-

luminating means within the box; Fig. 3 is a rear view of one form of front panel in which the individual identification means may be secured; Fig. 4 is an enlarged view 60 of a portion of the bottom of the house number box showing the means which I provide for lighting the house entrance below the box; Fig. 5 is a perspective view partially broken away and in section showing the arrangement of the panels by which I secure identification marks visible both during the day and at night to good advantage; Fig. 6 is a detailed view revolved at 90° showing one method of securing the front panel in 70 position relative to the house number box; Fig. 7 is a fragmentary rear view illustrating one method of securing the house number box to a vertical wall in lieu of chain suspension as illustrated in Fig. 1; Fig. 8 75 is a fragmentary plan view of the bracket construction represented in Fig. 7; Fig. 9 is a detailed view of one method of securing the individual sets of panels in the house number box; Fig. 10 shows the construction 80 of a pressed metal front panel for the house number box; Fig. 11 is a cross-sectional view of the house number box constructed of pressed sheet metal; Fig. 12 is a rear view of 85 the front panel frame showing the individual pressed metal boxes which are provided to carry the sets of identification panels; Figs. 13 and 14 show front and side views of the individual pressed metal boxes which support the sets of identification panels, and 90 Figs. 15 and 16 show methods of supporting the sheet metal house number box upon a vertical wall.

My present invention is an improvement upon the invention in house number boxes as 95 covered by my Patent 1,494,318, dated May 14, 1924. The advantages in the construction of my present invention over the invention as covered by my aforementioned patent will be more clearly understood by detailed reference to the drawings, in which:

Reference character 1 designates the combined day and night house number box having a front panel 2 containing cathedral or art glass panels showing the numbers 5 105 clearly visible in daylight, and when illuminated at night showing the numbers in a reddish glow clearly visible at a distance. The box 1 is closed at each end by ornamental side portions 6. Illuminating means 7 contained in a receptacle 8 is carried interiorly 110 of the box. An entrance conduit housing 9

is provided for conductors 10 which pass into the box. The illuminating means 7 serves not only to render the identification numbers clearly visible at night but also to 5 serve as an illumination means for the entrance where the light is deflected through slot 11 in the bottom of box 1. Slot 11 is covered by clear glass 12 secured in position by means of lugs 14 and 15 and end cleats 17 and 17^a. The fact that the clear glass 12 is 10 securely positioned adjacent the bottom of box 1 provides a dust and bug proof enclosure at the same time that the area immediately below the box may be illuminated. I 15 provide lugs 16 at the top of the box 1 in which chains 22 may be secured for suspending and making pendant the house number box from a ceiling 18 above a house entrance. I also provide lugs 19 at each rear bottom 20 end of the box to fasten or suspend the owner's name plate or plates, or other designating signs, below the house number box. The front frame panel 2 is fastened to the sides 6 of the box 1 by means of lugs 20 25 through which removable screws 21 pass and engage the sides 6. I might also provide a depression in each of the sides 6 into which a spring catch carried by frame 2 might be engaged.

29 In lieu of the pendant mounting for the box I may provide an invisible wall bracket 23 at the rear of the box. The bracket is formed of extended bar 24 which engages with the wall against which the box is to be 30 supported. By providing both the vertical lugs 16 and the rear socket members 29 and 30, I am enabled to mount the house number box on either a vertical or horizontal support.

40 A pair of arms are provided on opposite ends of the bracket 23 disposed substantially at right angles to the portion 24 as represented at 25 and 26. Upwardly extending tongues 27 and 28 are provided disposed at right angles to portions 25 and 26 of the bracket. These tongues are arranged to fit into socket members or straps 29 and 30 secured upon the rear wall of the box 1 and on opposite sides of the conduit housing 9. 45 These brackets 28 and 29 may be secured in position by means of screws 31 and 32 while the conduit housing 9 may be secured in position by means of screws 33 passing through lugs 34. I may construct the house number box of pressed metal in which case the socket members 29 and 30 would be pressed directly from the material of the box 1 as represented more clearly in Figures 11, 15 and 16. In 50 this event the housing 9 is forced over an outpressed cylindrical flange 25, the housing being frictionally or positively engaged with respect to said flange. The front panel frame 2 is divided into a plurality of sections in which the several identification characters are carried. In order that the num-

bers may be visible both during the day and at night I provide a unique arrangement of panels. In each section of the panel 2 I provide a transparent glazed surface 36 such as clear glass or mica. The characters are cut 70 from a stencil plate 37 which is non-transparent and preferably white. This stencil 37 is set back against the clear glass 36 and immediately adjacent thereto. Behind the stencil 37 I provide a sheet of cathedral or 75 art glass 38. Immediately behind the cathedral or art glass, which is preferably of amber color, I arrange a frosted glass 39. During the daylight the characters are shown in black without illumination. At night with 80 the illuminating means 7 in operation the amber, cathedral or art glass enables the characters to be shown in reddish glow. This characteristic color enables the characters to be visible for a long distance at night. 85 The laminated sheets making up the illuminated sections are secured in the panel frame 2 in a unique manner. I have shown the panel 2 consisting of a casting with sheet metal tongues 40 embedded therein, which 90 tongues are bent down upon the diffusing panel 39 thereby holding the panels in the frame sections. This arrangement of the tongues facilitates the changing of the numbers by straightening the tongues, removing 95 the diffusing panel 39 and art glass panel 38 and changing the stencil 37 as required and then replacing the several panels and bending down the lugs for holding the panels in 100 position.

When the frame member 2 is constructed of pressed metal the several sections of panels are housed within pressed sheet metal boxes 41 having a front opening arranged to correspond with the front opening of 105 the frame 2. Each of the metal boxes 41 is secured to the frame 2 by spot welding or other suitable fastening represented at 42 in the drawing. Tongues 43 are provided on the box section 41 enabling the several panel 110 sections to be secured in position and the numbers or letters changed at will.

The construction of the day and night house number box is such that it may be readily manufactured on a quantity production basis inexpensively. The box may be mounted either pendants over a house entrance or upon the wall adjacent the house entrance. The arrangement of the identification letters is such that the location of 120 houses at night is greatly facilitated while during the day the box presents an ornamental finish for the home.

I have illustrated certain preferred embodiments of my invention but I desire that 125 it be understood that modifications may be made and that I intend no limitations upon the invention other than those imposed by the scope of the appended claims.

What I claim and desire to secure by Let- 130

ters Patent of the United States is as follows:

1. A house number box comprising in combination a substantially rectangular housing having its front side open, illuminating means carried within said housing, a front plate for closing the front side of said housing and having an edge portion bent to fit around the edge of said housing, and a plurality of box-like frame members carried by said plate, and a plurality of plate members carried by each of said box-like frame members, said members comprising a diffusing panel, an art panel and a stencil plate contrasting in color with respect to said art panel with characters formed by said stencil plate, and means integral with each of said box-like frame members for securing said plates in position whereby said characters are normally visible in daylight and become equally visible at night when said illuminating means becomes effective.
2. A house number box comprising in combination a substantially rectangular housing having its front side open, illuminating means carried within said housing, a front plate for closing the front side of said housing, and having an inturned edge portion bent to conform with the shape of said housing, a plurality of box-like frame members carried by the inner side of said plate, each of said box-like members having edges turned inwardly and parallel with the inturned edge portion of said front plate, art

number plates and characters secured in each 35 of said box-like frame members, the edges of said housing being positioned between the inside wall of the inturned portion of said front plate and the outside portion of the inturned wall of said box-like frame members for locating said art number plates and characters before said illuminating means.

3. A house number comprising in combination a substantially rectangular housing having its front side open, illuminating 45 means carried within said housing, a front plate for closing the front side of said housing and having an edge portion bent to fit around the edge of said housing, and a plurality of box-like frame members carried by 50 said plate and positioned side by side and extending substantially the height of said front plate leaving a gap between the sides of said box-like frame members and said housing between which the edges of said 55 housing are gripped, and a plurality of plate members carried by each of said box-like frame members, said members comprising a diffusing panel, an art panel and a stencil plate contrasting in color with respect to 60 said art panel with characters formed by said stencil plate, and means integral with each of said box-like frame members for securing said plates in position whereby said characters are normally visible in daylight 65 and become equally visible at night when said illuminating means becomes effective.

GEORGE T. SHEARER.
